UNITED STATES PATENT OFFICE.

CHARLES MILLER, OF SYRACUSE, NEW YORK.

BELT-CARRIER.

No. 909,439.

Specification of Letters Patent.

Patented Jan. 12, 1909.

Application filed April 24, 1907. Serial No. 369,936.

To all whom it may concern:

Be it known that I, CHARLES MILLER, of Syracuse, in the county of Onondaga, in the State of New York, have invented new and 5 useful Improvements in Belt-Carriers, of which the following, taken in connection with the accompanying drawings, is a full, clear, and exact description.

This invention relates to belt-carriers 10 which are designed to be placed at the side of a driving-pulley to serve as a loose-pulley onto which the belt is to be shifted.

The main object of the present invention 15 is to produce a simple and reliable belt-carrier which can be easily and conveniently set in position while the shaft of the pulley is rotating, and which shall be entirely independent from the shaft so that the latter will be absolutely free from wear.

20 A further object of the invention is to produce a belt-carrier which can be readily and conveniently adjusted to allow it to be used in connection with pulleys of various sizes, and to provide simple and effectual anti-friction means which will facilitate the operation 25 of shifting the belt onto and off from the carrier.

Other objects of the invention will be apparent from the novel construction and arrangement of the component parts of the belt-carrier hereinafter fully described and set forth in the claims.

In the accompanying drawings Figure 1 is partly a side view and partly a sectional view 35 of the preferred form of my improved belt-carrier supported in operative position; Figs. 2 and 3 are vertical sections taken on the lines —X—X— and —Y—Y— respectively in Fig. 1; Fig. 4 is an enlarged detail 40 plan view of one of the belt-supporting bars employed in the preferred form of carrier; Fig. 5 is a vertical sectional view of a modified form of the belt-carrier; Fig. 6 is a detached view of the carrier-head employed in 45 the said modified construction; Fig. 7 is an enlarged detached plan view of one of the belt-supporting bars used in the latter construction; Fig. 8 is a fragmentary front view 50 of a belt-carrier embodying a further modification of the invention; and, Fig. 9 is partly a side view and partly a vertical sectional view of the carrier-head shown in Fig. 8.

Similar letters and numerals of reference 55 indicate corresponding parts in the various views:

—A— denotes a power-shaft journaled in suitable bearings on the usual hangers as indicated at —B—.

—C— denotes a driving-pulley secured to 60 the shaft, and —D— represents the belt traveling on said pulley.

My improved belt-carrier comprises essentially a revoluble head —1— journaled axially in line with the shaft —A— and provided with a plurality of horizontally disposed bars —2— which are set parallel with the shaft to support the belt —D— when the latter is shifted off from the pulley —C—. The carrier-head —1— generally 70 consists of a vertically disposed annular plate or disk as shown in Figs. 1, 2, and 3 of the drawings. The plate is formed with a tubular hub —3— which is journaled on a bearing-sleeve —4— supported on a hanger 75 —5— which may be fastened to any suitable object above the shaft as shown in Fig. 1. The said hanger is provided with a vertical slot —6— through its lower end and in said slot is preferably disposed the rear end of the 80 sleeve —4—. Said sleeve surrounds the shaft but is independent thereof and on its rear end portion it is formed with an external circumferential flange —7— which is detachably secured to the said hanger by 85 means of bolts —8—, and on the forward end of the sleeve is formed an external circumferential flange —9—, between which flanges the hub —3— of the head is confined. The said bearing-sleeve is provided in its 90 upper portion with an opening —10— extending throughout its length, said opening being of sufficient width to allow the shaft —A— to pass therethrough in the operation of attaching the sleeve to or detaching it 95 from the hanger —5—. By slotting the lower end of the said hanger as shown and described it is obvious that the same can be readily placed in position without interfering with the shaft.

100 The head or plate —1— is divided on a line extending diametrically through its hub, as indicated at —11—, in order to allow the same to be mounted on the flanged sleeve —4— and removed therefrom when required, 105 and the two sections of the hub are formed with corresponding longitudinal flanges —12— which are united by means of bolts —13— or other fastening devices. On the backs of the plate-sections are provided 110 two pairs of corresponding ears —14— disposed at the line of division, and through

said ears pass bolts —15—15—, whereby the two sections are more securely united.

The belt-supporting bars —2—2— are obviously connected to the head or plate at 5 points which are on a circular line concentric with the pulley —C—. Each of said belt-supporting bars comprises preferably a pair of parallel plates —a—a— between which are arranged a set of antifriction rollers —b—b— journaled on shafts —c—c— secured to the plates and disposed at right angles to the shaft —A—. These bars are designed to be adjusted on the head —1— so as to adapt the carrier to pulleys of different 15 diameters, and the rollers may project slightly beyond the plane of the face of the pulley owing to their shafts being at right angles to the pulley-shaft.

To obtain the aforesaid adjustment of the 20 belt-supporting bars, I prefer to provide the head or plate —1— with radial slots —16—16— into which the rear ends of the bars are inserted and in which they are adapted to slide longitudinally, said ends of the 25 bars being formed with screw-threaded studs —17—17— for the reception of nuts —18—18— by which they are clamped in position. It will be evident that by placing the rollers —b—b— in the position shown, the belt 30 can be shifted to and from the carrier with ease owing to the small amount of friction on the belt.

Any suitable and well known device may be employed for shifting the belt. In the 35 present instance I have shown a longitudinally movable horizontal rod —19— sliding in guides —20—20— provided on the lower end of a bracket —21— depending from the hanger —5—, said rod being provided with 40 the usual belt-receiving fork —22— at one end and having a hand-lever —23— pivotally connected to its opposite end.

While I prefer to form the adjustable belt-carrier as hereinbefore described, still, at the 45 same time the said carrier may be constructed as shown in Figs. 5 and 6 of the drawings. In this instance the head comprises a series of arms —24—24— extending radially from the hub —3—, on which arms the belt-supporting bars —2—2— are adjustably mounted. These arms —24—24— are preferably 50 inserted in sockets —25—25— on the hub and may be secured therein in any suitable manner, however, the said arms may be 55 formed integral with the hub if desired. The arms are preferably formed rectangular in cross-section and the belt-supporting bars —2—2— are provided with correspondingly shaped sleeves —26—26 through which 60 the arms pass, whereby the bars may be shifted to a greater or less distance from the hub to accommodate the carrier to pulleys of various sizes. The said bars in this instance are retained in their positions by 65 means of set-screws —27—27— passing

through the sleeves —26—26 and engaging the arms. The antifriction rollers —b—b— are applied to these belt-supporting bars in the manner hereinbefore described and as shown in Fig. 7 of the drawings.

Referring to Figs. 8 and 9 of the drawings, the head of the carrier consists of an ordinary wooden pulley. In this case, each belt-supporting bar comprises a base or attaching-plate —d— which extends across the face of the pulley and is curved correspondingly and a pair of parallel plates —a—a— extending preferably the entire length of the base or attaching-plate —d—, the rollers —b—b— being pivoted between the plates —a—a— as aforesaid and shown in Fig. 8.

While I prefer to form the bearing-sleeve —4— with a longitudinal opening for the purpose hereinbefore described, still at the same time it will be understood that the 85 same may be made in two parts like the hub —3—, therefore I do not limit myself in that respect. Furthermore I do not confine myself to placing the antifriction rollers with their shaft disposed at right angles to the 90 pulley-shaft, inasmuch as the angle may be varied as conditions may demand.

The described belt-carrier is subject to other modifications without departing from the spirit of the invention.

What I claim as my invention is:

1. The combination with a shaft, a pulley secured to said shaft, and a belt traveling on the pulley, of a revoluble belt-carrier supported axially in line with the shaft and independent thereof and provided with a plurality of sets of antifriction rollers onto which the belt is adapted to be shifted as set forth.

2. The combination with a shaft, a pulley secured to said shaft, and a belt traveling on the pulley, of a belt-carrier comprising a head supported revolubly and independently of the shaft and axially in line therewith, belt-supporting bars mounted on the head, and antifriction rollers pivoted to said bars 110 and having their axes disposed at an angle in relation to the shaft as set forth.

3. The combination with a shaft, a pulley secured to said shaft, and a belt traveling on the pulley, of a belt-carrier comprising a 115 revoluble member disposed axially in line with the shaft and supported independently thereof, a plurality of belt-supporting members each formed with a pair of parallel horizontal plates disposed longitudinally in relation to the shaft, and antifriction devices 120 confined between the plates of each member onto which the belt is adapted to be shifted as set forth.

4. The combination with a shaft, a pulley 125 secured to said shaft, and a belt traveling on the pulley, of a belt-carrier onto which the belt is adapted to be shifted, said carrier comprising a revolubly supported head disposed axially in line with the shaft and independ-

ently thereof, a series of belt-supporting bars mounted on the head and disposed radially in relation to the shaft, each of said bars composed of a pair of parallel plates spaced 5 apart, and a set of antifriction rollers pivoted between the plates of each bar and having their shafts disposed at an angle to the shaft as set forth.

5. The combination with a shaft, a pulley 10 secured to said shaft, and a belt traveling on the pulley, of a belt-carrier onto which the belt is adapted to be shifted, said carrier comprising a head supported revolubly and axially in line with the shaft, a series of belt- 15 supporting bars disposed parallel with the shaft and connected radially adjustable to the head, means for clamping the bars in their positions, and rollers pivoted to the said belt-supporting bars and having their axes 20 disposed at an angle to the shaft as set forth.

6. The combination with a shaft, a pulley 25 secured to said shaft, and a belt traveling on the pulley, of a belt-carrier onto which the belt is adapted to be shifted, said carrier comprising a suitably sustained hanger, a bearing-sleeve secured to the hanger and surrounding the shaft and independent of the latter, a head mounted revolubly on said sleeve, and a plurality of sets of belt-support- 30 ing rollers mounted on said head as set forth.

7. The combination with a shaft, a pulley 35 secured to said shaft, and a belt traveling on the pulley, of a belt-carrier onto which the belt is adapted to be shifted, said carrier comprising a suitable hanger provided with a vertical slot extending through its lower end and through which the shaft independently 40 passes, a bearing-sleeve secured detachably to the hanger at the slot and provided in its upper portion with an opening extending throughout its entire length and of a width

exceeding the diameter of the shaft, the said sleeve surrounding the shaft and being independent thereof, a head provided with a tubular hub mounted revolubly on the sleeve 45 and divided on a line extending diametrically through the hub, means for separably uniting the two sections of the head, and belt-supporting bars secured radially adjustable to the head as set forth. 50

8. The combination with a shaft, a pulley secured to the shaft, and a belt traveling on the pulley, of a belt-carrier onto which the belt is adapted to be shifted, said carrier comprising a suitable hanger provided with a vertical opening through its lower end, through which opening the shaft independently passes, a bearing-sleeve formed at one end with an external peripheral flange by which it is detachably secured to the hanger at the 60 opening and provided at its opposite end with an external peripheral flange, said sleeve being provided in its upper portion with an opening extending throughout its entire length and of a width exceeding the diameter of the shaft, and surrounding the said shaft and independent thereof, a radially-slotted head formed with a tubular hub mounted revolubly on the sleeve and confined between the flanges thereon and divided on a 65 line extending diametrically through the hub, means separably uniting the two head-sections, belt-supporting bars mounted adjustably in the slots of the head, and a set of antifriction rollers pivoted to each belt-supporting bar and having their axes disposed at an angle in relation to the shaft as set forth. 70 75

CHARLES MILLER.
